[57] CLAIM

The ornamental design for a shoulder pouch, as shown and described.

DESCRIPTION

FIG. 1 is a top plan view of a first embodiment of a shoulder pouch showing our new design;

FIG. 2 is a bottom plan view of the first embodiment;

FIG. 3 is a right side elevational view of the first embodiment;

FIG. 4 is a left side elevational view of the first embodiment;

FIG. 5 is a rear elevational view of the first embodiment;

FIG. 6 is a front elevational view of the first embodiment;

FIG. 7 is a top plan view of a second embodiment of the pouch of FIG. 1;

FIG. 8 is a bottom plan view of the second embodiment;

FIG. 9 is a right side elevational view of the second embodiment;

FIG. 10 is a left side elevational view of the second embodiment;

FIG. 11 is a rear elevational view of the second embodiment;

FIG. 12 is a front elevational view of the second embodiment;

FIG. 13 is a top plan view of a third embodiment of the pouch of FIG. 1;

FIG. 14 is a bottom plan view of the third embodiment;

FIG. 15 is a right side elevational view of the third embodiment;

FIG. 16 is a left side elevational view of the third embodiment;

FIG. 17 is a rear elevational view of the third embodiment; and,

FIG. 18 is a front elevational view of the third embodiment.

The broken lines in the figures of the third embodiment are for illustrative purposes only and form no part of the claimed design.
